DESIGN FOR A HOLDER FOR PARKING METER CHANGE

James S. MacDonnell, Denver, Colo.

Application April 17, 1944, Serial No. 113,275

Term of patent 7 years

(Cl. D52—4)

To all whom it may concern:

Be it known that I, James S. MacDonnell, a citizen of the United States, residing at Denver, in the county of Denver and State of Colorado, have invented a new, original, and ornamental Design for Holder for Parking Meter Change, of which the following is a specification, reference being had to the accompanying drawing, forming part thereof.

In the drawing:

Fig. 1 is a perspective view of a holder for parking meter change, showing my new design.

Fig. 2 is a horizontal sectional view taken on the line 2—2 in Fig. 1.

I claim:

The ornamental design for a holder for parking meter change, as shown.

JAMES S. MACDONNELL.
